W. J. TURNER,
SPRINKLER HEAD,
APPLICATION FILED DEC. 20, 1917.

1,314,169.

Patented Aug. 26, 1919.

UNITED STATES PATENT OFFICE.

WILLIAM J. TURNER, OF SAN FRANCISCO, CALIFORNIA.

SPRINKLER-HEAD.

1,314,169.

Specification of Letters Patent.

Patented Aug. 26, 1919.

Application filed December 20, 1917. Serial No. 208,000.

To all whom it may concern:

Be it known that I, WILLIAM J. TURNER, a citizen of the United States, and a resident of the city and county of San Francisco and State of California, have invented a new and useful Sprinkler-Head, of which the following is a specification.

My invention relates to automatic sprinkler heads for use in fire prevention systems.

10 An object of my invention is to provide a sprinkler head for automatically releasing a flow of water when the temperature in the vicinity of the head passes a fixed point.

15 Another object of my invention is to provide a sprinkler head in which the releasing structure is not rendered less sensitive by corrosive action, accumulations of dust and dirt, and disuse through a long period of years.

20 Another object of my invention is to provide a sprinkler head in which the collapse of the valve-holding means occurs with a snap which throws the holding members clear of the head frame.

25 Another object of my invention is to provide a sprinkler head highly resistant to mechanical injury.

The invention possesses other features of advantage, some of which, with the foregoing, will be set forth in the following description of the preferred form of my invention which is illustrated in the drawings accompanying and forming part of the specification. It is to be understood that I 30 do not limit myself to the showing made by the said drawings and description, as I may adopt variations of the preferred form within the scope of my invention as set forth in the claims.

40 Referring to the drawings:

Figure 1 is an elevation of the sprinkler head of my invention. The figure is drawn to an enlarged scale in order to show the structure more clearly, and portions are 45 shown in section.

Fig. 2 is an elevation showing a modified form of my invention.

Fig. 3 is a fragmentary view on a large scale, of a portion of the device.

50 Figs. 4 and 5 are perspective views of portions of the structure of the sprinkler head.

Fig. 6 is a perspective view of a portion of the sprinkler head shown in Fig. 2.

The sprinkler head of my invention comprises a frame 2 of well-known form provided with a nipple 3 wherewith the head is attached to the water supply pipe. At the opposite end of the frame a deflector 4 of the usual type is secured by a screw 6 integral therewith and which passes through a boss 7 forming the end of the frame. The screw 6 terminates in a blunt conical point 8 lying in the longitudinal axis A—B of the sprinkler.

In the base of the frame adjacent the nipple is a valve nozzle 9 upon which is seated a valve cap 12. Preferably a thin diaphragm or plate 13 of silver or comparable material is interposed between the valve cap and the nozzle end, so that the two will not become united by corrosion. The valve cap is formed with a curved top which terminates in a blunt conical point 14 lying in the axis A—B of the sprinkler. The rounded form of the valve cap is to prevent any possible catching of the members of the releasing means when the sprinkler opens.

Means are disposed between the two points 8 and 14 for retaining the valve cap 12 upon its seat under the water pressure existing in the sprinkler feed pipes. This means is arranged to collapse suddenly to release the valve cap, its parts being snapped clear of the frame, when the temperature in the neighborhood of the head rises above a predetermined point, usually 160° Fahrenheit.

The means for holding the valve cap tightly upon its seat consists of a triangularly-formed, three-piece strut, the members of which are held in normal operative position by means of solder so disposed between two of the members that a relatively larger bulk of solder and metal is disposed at a certain point than between said two members generally, so that when the temperature rises to the danger point, this larger mass of solder and metal is the last to fuse, resulting in the collapse of the strut with great suddenness, thus avoiding any possibility of water cooling the solder and consequent sticking and jamming of the solder-connected parts.

Referring first to Figs. 1, 4 and 5. The strut comprises a vertical compression member or post 16 lying in the axis of the sprinkler and provided with an integral arm 17 extending from the post preferably at about right angles. At one end of the post a seat is formed in which the conical point 8 rests. The other end of the post is turned a small amount to one side of the axis and is given 10 a blunt chisel-point which seats in a corresponding depression in the end of the lever 18. The lever 18 at this point is wider than the bottom edge of the post 16 so that transverse displacement of the post from its seat 15 is prevented. One end of the lever 18 is provided with a socket in which the conical point 14 of the valve cap is seated and the other end 19, of which is disposed in engagement with the arm 17. Preferably the 20 end 19 is turned at an angle to the main body so that it makes a surface contact with the under side of the arm 17 and extends outwardly toward the hooked end 21 of the arm. As seen in Fig. 1, the seat in the upper 25 side of the lever 18, in which the post 16 rests, is offset to the right of the axial line A—B, in which the point 14 of the valve cap bears upon the under side of the lever, so that the pressure of the cap 12 in the 30 axial line toward the point 8 tends to throw the end 19 of the lever 18 downwardly, swinging about the point 14 as a pivot; and this movement of the lever 18 is necessarily 35 accompanied by a swinging of the post 16 to the right, and a corresponding upward movement of the arm 17, about the point 8 as a pivot.

Means are provided for still further reducing the leverage ultimately to be exerted 40 upon the soldered joint, and for securing the lever 18 in operative position. A latch lever 22 is disposed upon the outside of lever 18, its upper end 23 being bent to conform with the lever 18 and to turn upwardly between the end of that lever and the hook 21. The extreme ends of the levers 18 and 22 are 45 preferably given rounded edges 24 and 25 respectively, which bear in correspondingly-formed sockets in the lever 22 and hook 21 respectively so that in the collapse of the parts, the ends of the levers roll easily out of contact. The ends of the two levers 18 and 22 are of spatulate form so as to provide a 50 broad surface contact with the under side of the arm 17 which is similarly formed. Between the ends of the levers and the arm 17 I interpose a thin plate 26 of silver or comparable material to prevent the uniting of these parts by corrosion. A web of material 55 is left on the sides of the hook 21 to prevent lateral displacement of the end of the latch lever 22.

Means are provided for holding the lower end of the latch lever securely against the

lever 18. It will be observed that owing to 65 the widely different lengths of the several lever arms formed, a very small restraining force at the lower end of lever 22 will hold a very large force tending to unseat the valve cap. Approximately midway between the 70 ends, the lever 18 is widened as best shown in Fig. 4, and from this widened portion a wing or tab 27 is raised at an angle of 90° to the main body of the lever. The lever 22, 75 Fig. 5, is similarly widened to coincide with the widened portion of the lever 18 and a tab or wing 28 stamped out of the end and turned outwardly at right angles to the body of the lever at the head of the recess 29. The wings 27 and 28 are so placed that when 80 the levers are assembled as shown in Fig. 1, the wings lie in contact with each other, the wing 27 projecting upwardly through the recess 29. Each of the wings 27 and 28 is provided with a hole, 31 and 32 respectively, 85 and when the levers are assembled the two holes are in alinement.

In assembling the strut members, the contiguous faces of the levers 18 and 22 are first 90 soldered together with solder having the desired fusing temperature and a mass of solder 33 disposed about the two wings 27 and 28 and through the alined holes 31 and 32. The solder thus not only cohesively unites 95 the two levers for the entire length of the shorter one but at the end of the long lever arm of the shorter lever 22 (said long lever arm extending downwardly from a point adjacent the rounded end 24 of the lever 18), forms a mechanical lock tending to prevent 100 the separation of the levers, since such separation would necessarily shear off the solder pin extending through the holes 31 and 32. It will also be noted that the mass of metal 105 accumulated about the wings will be somewhat slower to fuse than the solder lying between the two levers above this point; that is, when the fusing temperature is reached, the solder between the levers above the wings will first soften, so that when the 110 larger mass is finally affected an instant later, the lever latch lets go quite suddenly. This is a highly important feature and effectually eliminates all danger of sticking 115 or jamming of the parts, so often the result of a sluggish collapse. After the union of the two levers, they are assembled with the other strut member 16—17 and inserted in position between the points 14 and 8. The 120 screw 6 is then tightened by turning the deflector so that sufficient pressure is exerted to effectively hold the valve cap upon its seat against the water pressure in the feed pipes of the system. Preferably a locking pin 34 is riveted through screw 6 and boss 7 125 to prevent accidental loosening of the parts.

In case of fire in the vicinity of the sprinkler head, the solder between the levers

18 and 22 first melts and then the large mass fuses. At the instant of fusing, the stress tending to separate the levers causes lever 22 to swing downwardly and outwardly, pivoting about its end in the hook 21. This releases both the lever 18 and the remaining strut member 16-17 which are thrown out, as previously explained, allowing the water pressure to unseat the valve cap 12 and a stream of water to impinge upon the deflector 4.

The triangular form of the strut insures an open space between members which are to separate in operation. When members in a sprinkler, lying close to each other, are undisturbed for a long period, corrosion almost always causes a union of the adjacent or contiguous surfaces sufficient to impair if not wholly destroy the sensitiveness of the device. The large space left between the members in my sprinkler head effectually prevents such corrosive union. It should also be noted that in all parts of the sprinkler there is a metal-to-metal contact which renders the strut highly resistant to mechanical injury or deformation. Especially is this true of stresses produced by accidental blows upon the top of the lever 17. It is important that a sprinkler shall be so constructed that any mechanical injury will leave obvious effects, and not so bind or jam parts that the sprinkler will be inoperative, although apparently in good condition. The triangular form of my strut, together with the described relationship of the three parts, provides a structure which satisfactorily meets the requirements just indicated.

In the sprinkler head shown in Fig. 2, both structure and operation are the same in all respects as that just explained, except that a different means is used for securing the end of the long lever arm of the outer member 36. The lever 37 which corresponds to lever 18 of the Fig. 1 construction has an aperture 38 adjacent the end of the lever 36. In this aperture a key 39 is disposed. The key is roughly in the form of the letter T with a portion 41 of the shank bent so as to lie over the end of the lever 36. The cross bar of the key bears upon the surface of the lever 37 on both sides of the aperture. In assembling, the key is set against the upper edge of the aperture, the bent shank 41 in contact with and presenting an inclined edge to the edge of the lever 36. Solder is then flowed between the contiguous surfaces of the levers 36 and 37 and a mass of solder 42 is disposed around the end of the lever 36, the key and through the aperture 38.

When the temperature of the parts is raised to the fusing point of the solder, the solder between the lever faces first melts and this is followed by the fusing of the larger mass, thus permitting the key 39 to

be crowded down by the outward pressure of the end of the lever 36 on its slanting face. This results in an almost instantaneous release of the lever 36 and the resultant collapse of the strut and release of water from the nozzle.

70

I claim:

1. In an automatic sprinkler, a valve cap, a lever bearing on said cap, a post supported at one of its ends on the axial line of the sprinkler and bearing at its other end on the said lever to one side of the axial line, an arm extending from said post into engagement with said lever, a latch lever interposed between the ends of said arm and said first-named lever, said levers and said arms being of spatulate form at their contacting ends, and a fusible solder forming a cohesive and mechanical lock between said levers.

2. In an automatic sprinkler, a valve cap, a lever bearing on said cap, a post supported at one of its ends on the axial line of the sprinkler and bearing at its other end on the said lever to one side of the axial line, an arm extending from said post past the end of said lever, a latch lever interposed between the ends of said arm and said first-named lever, a non-corrosive plate interposed between said arm and said levers, and a fusible solder forming a cohesive and mechanical lock between said levers.

3. In an automatic sprinkler, a valve cap, a lever bearing on said cap, a post supported at one of its ends on the axial line of the sprinkler and bearing at its other end on the said lever to one side of the axial line, an arm extending from said post past the end of said lever, a latch lever interposed between the ends of said arm and said first-named lever, a wing on said first-named lever, a wing on said latch lever in contact with said first-named wing, and a fusible solder uniting the contiguous surfaces of said levers and massed about said wings.

4. In an automatic sprinkler having the characteristics set forth in claim 3, said wings provided with alined apertures and said massed solder forming a solder pin therethrough.

5. In an automatic sprinkler, a valve cap, a lever bearing on said cap, a post supported at one of its ends on the axial line of the sprinkler and bearing at its other end on the said lever to one side of the axial line, an arm extending from said post past the end of said lever, a latch lever interposed between the ends of said arm and said first-named lever, a wing on said first-named lever, a wing on said latch lever in contact with said first-named wing, said wings being formed with alined apertures therein, and a fusible solder pin disposed in said apertures.

6. In an automatic sprinkler, a valve cap, a lever bearing on said cap, a post supported

at one of its ends on the axial line of the sprinkler and bearing at its other end on said lever to one side of the axial line, an arm extending from said post past the end of 5 said lever, a wing projecting from said lever, a latch lever interposed between the ends of 10 said arm and said first-named lever and extending longitudinally along the latter, a wing on said latch lever adjacent to said first 15 wing, and a fusible solder massed about said wings.

7. In an automatic sprinkler, a valve cap, a lever bearing on said cap, a post supported at one of its ends on the axial line of the 15 sprinkler and bearing at its other end on said lever to one side of the axial line, an

arm extending from said post past the end of said lever, a wing projecting from said lever, a latch lever interposed between the ends of 20 said arm and said first-named lever and extending longitudinally along the latter, a wing on said latch lever adjacent to said first wing, said wings being provided with alined apertures, and a fusible pin disposed in said apertures. 25

In testimony whereof, I have hereunto set my hand at San Francisco, California, this 11th day of December, 1917.

WILLIAM J. TURNER.
